INTERCOMMUNICATION TELEPHONE SYSTEM.

APPLICATION FILED NOV. 4, 1902.

UNITED STATES PATENT OFFICE.

RICHARD M. BEARD, OF NEW YORK, N. Y.

INTERCOMMUNICATION TELEPHONE SYSTEM.

No. 809,929.

Specification of Letters Patent.

Patented Jan. 16, 1906.

Application filed November 4, 1902. Serial No. 130,054.

To all whom it may concern:

Be it known that I, RICHARD M. BEARD, a citizen of the United States of America, and a resident of New York, in the county of New York and State of New York, have invented certain new and useful Improvements in Intercommunication Telephone Systems, of which the following is a specification.

My invention relates generally to telephone systems, and specifically to a secret-service or private line system of intercommunication from one station to another without the necessity of a central office and without the serious objection of a third party being able through any manipulation of his own telephone apparatus or switching devices to listen in while two other parties are in communication. No complicated or unusual mechanism is needed in my system, privacy being secured through the disposition of circuits. The number of subscribers is limited only by the amount of space at the disposal of each party for the location of the installation and by the inconvenience of leading into each station the necessarily large number of wires, or cable containing the leading-in wires, for the telephone.

I have found that the intercommunication systems in present operation, either by reason of securing no privacy to conversations or by reason of complicated and easily-disordered automatic devices to prevent same, are not adapted to the needs of groups of men in a particular line of business—such as stock-brokers, financiers, and dealers in valuable commodities—where telephonic communication is of limited value unless absolutely private. The number of such users requiring private-line service among themselves seldom exceeds ten.

My system is especially designed to meet the needs of parties requiring absolutely private telephonic intercommunication. It is equally adapted to be used as a house system in hotels, apartment-houses, department-stores, general offices, private dwellings, mills, factories, hospitals, or other institutions, war vessels, or ships of any class and may be used as a community system in villages, ship-yards, mines, and other isolated districts where telephonic interservice is desired without the expense of maintaining a central office and operators. In any of the above-mentioned uses secret service is of value only in a lesser degree than in the case

of the parties for which my system is specifically designed.

Generally the organization comprising my invention consists of the combination of telephone, signaling, and switching apparatus located at each of three or more stations and a system of interconnecting lines comprising independent wires for respectively connecting the apparatus at each one of the stations with the apparatus at each one of the remaining stations. The disposition of the local circuits and apparatus, with the exception of the keys, which are intermediary between the different groups of apparatus and the interconnecting lines, is in two general groups, and each of the groups is connected to a separate pair of contact-springs on the keys by an independent pair of wires. One of the general groups may be termed the "telephone" and "signal-sending" group, and by means of switching-contacts located in and forming a part of the apparatus comprised in this group talking and signaling may be alternately done over the same pair of wires leading to the keys. The other of the two general groups may be termed the "signal-receiving" group, and the apparatus of this group consists of visual signals and an audible signal, which are so connected together through switching contacts forming a part of the visual mechanisms that the audible signal may operate simultaneously with any one of the visual signals over the same pair of wires leading to the keys. The function of the keys located at each station is to connect the circuits leading to each of the other stations alternately with either of the two general groups of apparatus. In order that this may be done, the moving arms of the keys, which are virtually double-pole double-throw switches, are connected to the pair of wires leading to the station to which each key respectively corresponds. Of the other two pairs of contacts, with each of which the moving arms are alternately in contact, the one is connected to the one of the general groups, while the remaining pair of contacts is connected to the other of the two general groups of apparatus.

In view of the limited space on the sheets of drawings only three stations are represented completely.

Figure 1 is a general view of the complete system in a normal condition applied to three stations and showing the common re-

turn method of interconnecting lines. Fig. 2 shows the complete interwiring for connecting ten stations, in which a common return-wire is also used. The telephone apparatus and local wiring for each station is omitted from this drawing.

The apparatus and local wiring at each of the stations shown in Fig. 1 is exactly the same. Some of the apparatus—as, for example, the transmitter and receiver—is shown as exterior elevations; but most of it is represented diagrammatically and typically.

The different stations shown in the drawings and indicated, respectively, as Sta. 1, Sta. 2, and Sta. 3 may be known as "station 1," "station 2," and "station 3," while there may be further stations at Sta. 4, Sta. 5, Sta. 6, Sta. 7, Sta. 8, Sta. 9, and Sta. 10. At each of the stations there is a connecting-strip, (indicated at Sta. 1 as cs' , at Sta. 2 as cs^2 , at Sta. 3 as cs^3 , and so on the connecting-strips are indicated at each of the remaining stations.) On each of the connecting-strips there is a set of terminals or binding-posts, and the terminals are numbered from left to right beginning with 0 and omitting the number corresponding to the number of the strip—i. e., the number of the station at which the strip is located. For example, the terminals on the connecting-strip cs' are numbered from left to right, 0 2 3, &c. The terminals on the strip cs^2 are numbered 0 1 3, &c., while the terminals on the strip cs^3 are numbered 0 1 2, omitting 3, and so on. The common wire is numbered 0—0 and is connected to the terminal numbered 0 at each of the connecting-strips. The wire numbered 1—2 is connected at cs' with terminal 2 and at cs^2 with terminal 1 and is the independent wire between Sta. 1 and Sta. 2. The wire numbered 1—3 is connected at cs' with terminal 3 and at cs^3 with terminal 1 and is the independent wire between Sta. 1 and Sta. 3. The wire numbered 2—3 is connected at cs^2 with terminal 3 and at cs^3 with terminal 2 and is the independent wire between Sta. 2 and Sta. 3, and so on in like manner each of the independent wires are numbered. The independent wire in each case, together with the common wire, forms a complete electrical circuit between the two stations in which the independent wire terminates.

The keys are represented in Fig. 1 in the typical manner commonly employed in telephone drawings. The keys at Sta. 1 are designated k'^2 and k'^3 , because they are the keys at Sta. 1 which connect through the terminals on the connecting-strip cs' to the circuits leading, respectively, to Sta. 2 and Sta. 3, the keys at Sta. 2 are designated k'^1 and k'^2 , because they are the keys at Sta. 2 which connect through the terminals on the connecting-strip cs^2 to the circuits leading, respectively, to Sta. 1 and Sta. 3, and the keys

at Sta. 3 are designated k'^1 and k'^2 , because they are the keys at station 3 which connect through the terminals on the connecting-strip cs^3 to the circuits leading, respectively, to Sta. 1 and Sta. 2.

The keys k' k'' , &c., are all shown in the drawings in normal position, in which position the moving arms or middle contact-springs A' , which are connected in each case to the outgoing circuit, are in contact with the inside springs which are connected to the signal-receiving group. The outside contact-springs, which in each case are connected to the telephone and signal-sending group, are normally open.

Located just above and directly connected to the inside contact-springs of each key is a visual signal or drop. The drops at Sta. 1 are designated d'^2 and d'^3 , because they are the drops located at Sta. 1 which indicate, respectively, calls from Stas. 2 and 3, those at Sta. 2 are designated d'^1 and d'^3 , because they are the drops at Sta. 2 which indicate, respectively, calls from Stas. 1 and 3, and those at Sta. 3 are designated d'^1 and d'^2 , because they are the drops at Sta. 3 which indicate, respectively, calls from Stas. 1 and 2.

A magneto-electric bell is located at each of the Stas. 1, 2, and 3 and designated, respectively, m' , m'' , and m''' . The magneto-bell is the audible signal forming a part of the signal-receiving group at each station.

The transmitters t' , t'' , and t''' , the receivers r' , r'' , and r''' , the induction-coils i' , i'' , and i''' , the primary battery b' , b'' , and b''' , and the receiver-hooks h' , h'' , and h''' are located, respectively, at each of the Stas. 1, 2, and 3. They form at each of the stations the telephone set proper and are a part of the telephone and signal-sending group.

A magneto-electric generator is located at each of the Stas. 1, 2, and 3 and designated, respectively, g' , g'' , and g''' . They are at each of the stations a part of the telephone and signal-sending group.

All of the detail parts of the generators being well known are not shown; but it may be well in this connection to explain that while the wire 11 is constantly connected with one end of the armature-winding the wire 33 only makes contact with the other end of the armature-coil when the crank c is operated, the operation of the crank electrically closing a pair of normally open contacts in the usual manner.

It is unnecessary to explain further details of the construction of the system, and therefore the operation may now be explained.

Let it be assumed that Sta. 1 desires to call and talk with Sta. 3. The party at Sta. 1 throws the key k'^3 —that is, the key the movable arms A' A'' of which connect to the circuit leading to Sta. 3—into the other position. All the details of the keys are not represented because well known; but for the pur-

pose of explaining the operation it may be assumed that when the key k^3 is thrown into the other position the wedge w is pushed in directly between the movable arms $A' A'$ far enough to cause them to break contact with the inside springs and make contact with the outside pair of springs and to remain in that position until such time as it is desired to throw the key back into the normal position. 5 When the key k^3 is thrown into the position as described above, the signal - receiving group is disconnected from and the telephone and signal-sending group connected with the circuit 0—0 1—3 leading to Sta. 3. Then in 10 order to signal Sta. 3 the party at Sta. 1 turns the crank c of his generator g' and by tracing the wires leading from the generator g' , one, 11, making circuit with wire 22 through the contact n of the receiver-hook h' , the 15 other, 33, leading direct to the key k^3 , and, remembering the changed position of the key k^3 , it will be seen that the alternating current generated passes out over the circuit 0—0 1—3 leading to Sta. 3. Having traced 20 the path of the current passing through the key k^3 and leading out from Sta. 1 over the terminals 0, 3 on the connecting-strip cs' , the outside wires 0—0 1—3 bring the current into Sta. 3 over the terminals 0, 1 of the connecting-strip cs^3 and passing on through the 25 key k'''_1 , which is of course in the normal position as indicated in the drawings, the circuit is closed through the winding v of the drop d'''_1 . That which takes place at Sta. 3 is 30 that when the alternating currents passing through the winding v of the drop d'''_1 , magnetizing the core v' , which at pole e alternately attracts and repels the armature a and causes the arm f to vibrate, thereby instantly 35 releasing the brass shutter s , which falls forward, disclosing on the face of the drop d'''_1 the number of the station calling and also closing the commonly-called night-bell contact x' at the terminal x , whereby the magneto-bell m''' is thrown into multiple circuit 40 with drop d'''_1 , continuing to ring as long as the party at Sta. 1 continues to turn the generator g' . Having signaled Sta. 3, the party 45 at Sta. 1 lifts his receiver r' from the hook h' and places it to his ear. The receiver-hook h' being released is lifted by the spring l , thus breaking contact at n , cutting the generator g' out of circuit, and also making contact at p and q , thereby closing the telephone 50 set at Sta. 1 with the circuit which has just been traced leading to Sta. 3. The party at Sta. 3 having received the signal from Sta. 1 may restore the shutter s of the drop d'''_1 , taking note of the number, throw the key 55 k'''_1 corresponding to it into the other position, and lift his receiver r''' from the hook h''' , whereby he is then in actual telephone connection with the party at Sta. 1. In 60 throwing the key k'''_1 into the other position 65 the party at station 3 cuts the signal-receiving

group out of circuit and connects the telephone signal-sending group into circuit with the wires leading to Sta. 1 in the same manner as the key k^3 was operated at Sta. 1, and when the receiver r''' is removed the hook h''' being released cuts the generator out of circuit and switches the telephone set into circuit in the same manner as the hook h' operated at Sta. 1. When the two parties have finished talking, each returns his receiver to the hook and restores the key, which he has thrown into reverse position, back into the normal position, and each party is then ready to again be signaled. 70 75

It will be noticed that when one party 80 calls another, as the party at Sta. 1 called Sta. 3, that the party calling does not get actual telephone connection with the party called until the party being called desires to connect him into circuit for that purpose. 85 So that if while Stas. 1 and 3 were in conversation the party at Sta. 2 should call Sta. 1, for instance, the party at Sta. 1 need not connect Sta. 2 into circuit while talking with Sta. 3. The party at Sta. 2 may lift his receiver from the hook after having thrown the key for talking to Sta. 1, thereby connecting his own telephone set in on the circuit leading to Sta. 1; but he will merely be listening in on the drop and magneto-bell at Sta. 1 as 90 long as the key at Sta. 1 corresponding to the circuit leading to Sta. 2 remains in the normal position, and the party at Sta. 2 will therefore be unable to hear the conversation between Stas. 1 and 3. The party at Sta. 1 95 may say to the party at Sta. 3 "Hold the wire one minute," and instantly switch Sta. 3 out of circuit and switch Sta. 2 into circuit with his own set and say to the party at Sta. 2 "Am busy; will call you," and as quickly 100 cut Sta. 2 out of circuit and Sta. 3 into circuit, again resuming his conversation with the party at Sta. 3. It is not necessary, however, that the party at Sta. 1 should cut Sta. 3 out of circuit while answering Sta. 2, and 105 the party at Sta. 2 may even become a party to a general conversation between the party at Sta. 1, the party at Sta. 3, and himself. 110

The construction of the system and its operation as already explained illustrate its 115 uses sufficiently well. Other forms, however, of apparatus which accomplish similar results may be substituted for the exact forms shown in the drawings without altering the basic principles of the invention—viz., the 120 disposition of the local circuits, the arrangement of the interconnecting circuits, and the method of switching. In any case the telephone when in use is maintained in an independent balanced local circuit. The interconnecting circuits comprise independent circuits for respectively connecting each station with each one of the remaining stations, and in the method of switching two operations are always necessary to connect the 125 130

telephones of two stations together—namely, the operation of the switches at the station calling and the operation of the switches at the station called.

- 5 It is obvious that earth return may be substituted for the metallic common return shown in the drawings; but the danger of line disturbances would be increased thereby, and it is doubtful whether the saving of one 10 wire would in any case justify the change. Attention is directed to the fact that in Fig. 2 the common return-wire is a complete loop—*i. e.*, it is continuous in one direction from each station to every other station and 15 back to the first-mentioned station from the other direction. This is thought to be an advantage, as the return is thus completed between any two stations in two directions and the liability of cross-talk incidental to the 20 use of a common return lessened without increasing the size of the conductor. If the common return-wire were broken at any one point in the loop, service would not be interrupted. Attention is further directed to the 25 fact that in Fig. 2 the interconnecting lines branch about equally in two directions from each station. In this way a uniform-sized cable can be used throughout which has a less number of conductors than will be required 30 between most of the stations when the cable-loop is not continuous and complete. This plan also secures to each independent line the shortest distance of paralleling any one of the other independent 35 lines, thus lessening the chances of cross-talk by induction between the independent lines, and the plan may always be conveniently used where the stations are not all located at points in a right line, which is rarely the 40 case. Furthermore, this plan is cheaper than twin-pair twisted or transposed metallic circuits between the stations and for ordinary distances has been found to be equally as free from cross-talk.
- 45 I am aware that various other inventors have made use of independent wires for respectively connecting each station with each one of the other stations, but no one, so far as I know, has taken all the precautions necessary 50 to secure absolute privacy in communications as I have done. To overhear conversations by induction destroys secrecy just as effectively as being able to cut in on the circuits.
- 55 By the use of the term “local” in this specification in reference to the wiring it is intended to distinguish the wiring at each station from the interconnecting lines. The interconnecting wires are considered to lose 60 their identity as such in the first piece of apparatus they connect to at each station, which is essential to the proper operation of the system—*viz.*, the switches. The connecting-strips are only used for convenience in 65 keeping trace of the wires at each station

and may be entirely omitted. It is not, however, intended to be inferred by the use of the word “local” that the circuits so designated are secondary in character.

I claim as my invention—

70 1. An intercommunication telephone system consisting of the combination of interwiring connecting three or more stations with one another, telephone apparatus at each station, signal-sending apparatus at each station, a separate group of wiring for said telephone and signal-sending apparatus, located at each station, signal-receiving apparatus and a separate group of wiring therefor at each station, and devices at the respective stations for electrically connecting the interwiring between any two stations, first to one group of wiring at one station, and then to the other group at the same station, said interwiring comprising independent wires for respectively connecting the apparatus at each one of the stations, with the apparatus at each one of the remaining stations.

75 2. An intercommunication telephone system consisting of the combination of interwiring connecting three or more stations with one another, telephone apparatus at each station, signal-sending apparatus at each station, a group of wiring for said telephone and signal-sending apparatus, located at each station, signal-receiving apparatus and a group of wiring therefor at each station, and devices at the respective stations for electrically connecting the interwiring between any two stations, first to one group of wiring at one station, and then to the other group at the same station, said interwiring comprising of a common return-wire for all the stations, and independent wires 80 respectively connecting the apparatus at each one of the stations, with the apparatus at each one of the remaining stations, said devices consisting of a switch, two of whose terminals are connected to said interwiring, two to one of said groups, and the remaining two to the other group.

85 3. An intercommunication telephone system consisting of the combination of interwiring connecting three or more stations with one another, telephone apparatus at each station, signal-sending apparatus at each station, a group of wiring for said telephone and signal-sending apparatus, located at each station, signal-receiving apparatus and a group of wiring therefor at each station, and devices at the respective stations for electrically connecting the interwiring between any two stations, first to one group of wiring at one station, and then to the other group at the same station, said interwiring comprising of a common return-wire for all the stations, and independent wires 90 respectively connecting the apparatus at each one of the stations, with the apparatus at each one of the remaining stations, said devices consisting of a switch, two of whose terminals are connected to said interwiring, two to one of said groups, and the remaining two to the other group.

95 4. An intercommunication telephone system consisting of the combination of interwiring connecting three or more stations with one another, telephone apparatus at each station, signal-sending apparatus at each station, a group of wiring for said telephone and signal-sending apparatus, located at each station, signal-receiving apparatus and a group of wiring therefor at each station, and devices at the respective stations for electrically connecting the interwiring between any two stations, first to one group of wiring at one station, and then to the other group at the same station, said interwiring comprising of a common return-wire for all the stations, and independent wires 100 respectively connecting the apparatus at each one of the stations, with the apparatus at each one of the remaining stations, said devices consisting of a switch, two of whose terminals are connected to said interwiring, two to one of said groups, and the remaining two to the other group.

105 5. An intercommunication telephone system consisting of the combination of interwiring connecting three or more stations with one another, telephone apparatus at each station, signal-sending apparatus at each station, a group of wiring for said telephone and signal-sending apparatus, located at each station, signal-receiving apparatus and a group of wiring therefor at each station, and devices at the respective stations for electrically connecting the interwiring between any two stations, first to one group of wiring at one station, and then to the other group at the same station, said interwiring comprising of a common return-wire for all the stations, and independent wires 110 respectively connecting the apparatus at each one of the stations, with the apparatus at each one of the remaining stations, said devices consisting of a switch, two of whose terminals are connected to said interwiring, two to one of said groups, and the remaining two to the other group.

115 6. An intercommunication telephone system consisting of the combination of interwiring connecting three or more stations with one another, telephone apparatus at each station, signal-sending apparatus at each station, a group of wiring for said telephone and signal-sending apparatus, located at each station, signal-receiving apparatus and a group of wiring therefor at each station, and devices at the respective stations for electrically connecting the interwiring between any two stations, first to one group of wiring at one station, and then to the other group at the same station, said interwiring comprising of a common return-wire for all the stations, and independent wires 120 respectively connecting the apparatus at each one of the stations, with the apparatus at each one of the remaining stations, said devices consisting of a switch, two of whose terminals are connected to said interwiring, two to one of said groups, and the remaining two to the other group.

125 7. An intercommunication telephone system consisting of the combination of interwiring connecting three or more stations with one another, telephone apparatus at each station, signal-sending apparatus at each station, a group of wiring for said telephone and signal-sending apparatus, located at each station, signal-receiving apparatus and a group of wiring therefor at each station, and devices at the respective stations for electrically connecting the interwiring between any two stations, first to one group of wiring at one station, and then to the other group at the same station, said interwiring comprising of a common return-wire for all the stations, and independent wires 130 respectively connecting the apparatus at each one of the stations, with the apparatus at each one of the remaining stations, said devices consisting of a switch, two of whose terminals are connected to said interwiring, two to one of said groups, and the remaining two to the other group.

one of the remaining stations, said devices consisting of a switch, two of whose terminals are connected to said interwiring, two to one of said groups, and the remaining two 5 to the other group, and a wedge for controlling the connections of all the terminals.

4. An intercommunication telephone system consisting of the combination of telephone and signal apparatus, located at each 10 of three or more stations, a system of interconnecting lines comprising independent wires for connecting each station respectively with each one of the other stations, a system of local wiring for connecting up the apparatus 15 at each station, which last-named system includes an independent balanced circuit for the telephone apparatus, and electric switches at each station for cutting in the said telephone apparatus at that station on 20 any pair of wires, while maintaining it disconnected from any of the other pairs of wires, whereby when any two stations are telephonically connected, no other station can listen in to either said two stations.
- 25 5. An intercommunication telephone system consisting of the combination of telephone and signal apparatus, located at each of three or more stations, a system of interconnecting lines comprising independent 30 wires for connecting each station respectively with each one of the other stations, a system of local wiring for connecting up the apparatus at each station, said last-named system including an independent balanced circuit 35 for the telephone apparatus, and electric switches at each station for cutting in the said telephone apparatus at that station on any pair of wires, while maintaining it disconnected from any of the other pairs of 40 wires, whereby when any two stations are telephonically connected, no other station can listen in to either said two stations, said telephone apparatus consisting of a transmitter, receiver and induction-coil located at 45 each of said stations, and an electric generator for supplying a current to said telephone apparatus, and said signal apparatus consisting of a single audible signal located at each of said stations, as many visual signals 50 at each station, as there are stations less one, and an electric generator for operating said signal apparatus.
- 55 6. An intercommunication telephone system consisting of the combination of telephone, signal-sending and signal-receiving apparatus, located at each of three or more stations, a common return-wire for the apparatus at all the stations, and independent wires respectively connecting the apparatus 60 at each one of the stations with the apparatus at each one of the remaining stations, two groups of local wiring at each station, keys at each station, each group of wiring being connected to a separate pair of contacts 65 tact springs on the keys by an independent

pair of wires, one group including the telephone and signal-sending apparatus, switching contacts located in and forming a part of the apparatus located in this last-named group, the other group being the signal-receiving group of wiring, and including visual signals and an audible signal, other switching contacts forming a part of each visual mechanism and operated thereby, the audible signal being connected in multiple with each 70 visual signal through each pair of said switching contacts, whereby the audible signal may operate simultaneously with any one of the visual signals.

7. An intercommunication telephone system, consisting of a telephone instrument located at each of three or more different stations, signals at each station, a device at each station for operating the signals at each one of the other stations, a system of interconnecting lines comprising independent wires, for connecting the apparatus at each station respectively with the apparatus at each one of the other stations, and means at each station for including any of said apparatus 80 in circuit with the interconnecting lines leading to any other station, said means, when connected for telephoning, including only the telephone instrument in said circuit, said telephone instrument being connected 85 with said means in a balanced independent local circuit, while the signals alone are included in circuit with the wires leading to the other stations, whereby complete privacy is secured between any two or more telephones which are connected for telephoning and at the same time each busy station is maintained available to be signaled by other stations.

8. An intercommunication telephone system consisting of the combination of telephone, signal-sending, signal-receiving and switching apparatus, a system of interwiring connecting the above elements, said telephone apparatus consisting of a telephone 105 instrument located at each of three or more stations, said signal-sending apparatus comprising a device at each of said stations for operating signals at any other station, said signal-receiving apparatus including signals 110 at each station to indicate the station from which the signals are operated, and the said switching apparatus consisting of a means at each station for cutting in, either the said telephone apparatus at that station, or the 115 said signal-sending apparatus, on any pair of wires, while maintaining it disconnected from any of the other pairs of wires, and for simultaneously cutting out the signal-receiving apparatus at the same said station from the said first-named pair of wires, and a balanced independent local circuit for the said telephone apparatus at each station and in which said telephone is wired to said means.

9. An intercommunication telephone sys- 130

tem consisting of the combination of interwiring connecting three or more stations with one another, telephone apparatus at each station, signal - sending apparatus at each station, a separate group of wiring for said telephone and signal-sending apparatus, located at each station, signal-receiving apparatus including a means for indicating the stations from which signals come, and a separate group of wiring therefor at each station, and devices at the respective stations for electrically connecting the interwiring between any two stations, first to one group of wiring at one station, and then to the other group at the same station.

10. An intercommunication telephone system consisting of the combination of telephone and signal apparatus, located at each of three or more stations, a common return-wire for all the stations, a single wire connection from each station to each other station, a system of local wiring for connecting up the apparatus at each station, said last-named system including an independent balanced circuit for the telephone apparatus, and electric switches at each station for cutting in the said telephone apparatus at that station on any one or more of the pairs of wires, while maintaining it disconnected from any of the other pairs of wires, whereby when any two or more stations are telephonically connected, no other station can listen in on the circuit connecting said two or more stations.

11. An intercommunication telephone system consisting of the combination of telephone and signal apparatus, located at each of three or more stations, a common return-wire for all the stations, a single wire connection from each station to each other station, a system of local wiring for connecting up the apparatus at each station, said last-named system including an independent balanced circuit for the telephone apparatus, and electric switches at each station for cutting in the said telephone apparatus at that station on any one or more of the pairs of wires, while maintaining it disconnected from any of the other pairs of wires, whereby when any two or more stations are telephonically connected, no other station can listen in on the circuit connecting said two or more stations, said telephone apparatus consisting of a transmitter, receiver and induction-coil located at each of said stations, and an electric generator for supplying a current to said telephone apparatus, and said signal apparatus consisting of a single audible signal located at each of said stations, as many visual signals at each station, as there are stations less one, and an electric generator for operating said signal apparatus.

12. An intercommunication telephone system consisting of the combination of telephone and signal apparatus, located at each of three or more stations, a common return-

wire for all the stations, a single wire connection from each station to each other station, a system of local wiring for connecting up the apparatus at each station, and electric switches at each station for cutting in the said telephone apparatus at that station on the common return-wire and on any one or more of the single wires, while maintaining it disconnected from any of the other single wires, and for simultaneously cutting out the signal apparatus at the same station from the said first-named single wire or wires.

13. An intercommunication telephone system consisting of the combination of interwiring connecting three or more stations with one another, telephone apparatus at each station, signal - sending apparatus at each station, a separate group of wiring for said telephone and signal-sending apparatus, located at each station, signal-receiving apparatus and a separate group of wiring therefor at each station, and devices at the respective stations for electrically connecting the interwiring between any two stations, first to the signal-receiving group of wiring at one station, and then to the telephone and signal-sending group of wiring at the same station, said interwiring comprising independent wires for respectively connecting the apparatus at each one of the stations, with the apparatus at each one of the remaining stations.

14. An intercommunication telephone system consisting of the combination of telephone, signal - sending, signal - receiving and switching apparatus, a system of interwiring connecting the above elements, said telephone apparatus consisting of a telephone instrument located at each of three or more stations, said signal - sending apparatus comprising a device at each of said stations for operating signals at any other station, said signal-receiving apparatus including signals at each station to indicate the station from which the signals are operated, independent local circuits for the telephone apparatus and for the signal-receiving apparatus, a local circuit for the signal-sending apparatus in multiple with the telephone local circuit, the said switching apparatus consisting of a means at each station for cutting in either the said telephone apparatus at that station, or the said signal - sending apparatus, on any pair of wires, while maintaining it disconnected from any of the other pairs of wires, and for simultaneously cutting out the signal-receiving apparatus at the same said station from the said first-named pair of wires.

15. An intercommunication telephone system, consisting of the combination of telephone, signal - sending, signal - receiving and switching apparatus, a system of interwiring connecting the above elements, said telephone apparatus consisting of a telephone instrument located at each of three or more sta-

tions, said signal-sending apparatus comprising a device at each of said stations for operating signals at any other station, said signal-receiving apparatus including signals at each station to indicate the station from which the signals are operated, and the said switching apparatus consisting of a means at each station for cutting in the said telephone apparatus at that station on any one or more of the pairs of wires, while maintaining it disconnected from any of the other pairs of wires, and for simultaneously cutting out both the signal-sending and the signal-receiving apparatus at the same said station from the said first-named one or more pairs of wires.

16. An intercommunication telephone system consisting of the combination of telephone, signal-sending, signal-receiving and switching apparatus, a system of interwiring connecting the above elements, said telephone apparatus consisting of a telephone instrument located at each of three or more stations, said signal-sending apparatus comprising a device at each of said stations for operating signals at any other station, said signal-receiving apparatus including signals at each station to indicate the station from which the signals are operated, and the said switching apparatus consisting of a means at each station for cutting in, either the said telephone or signal-sending apparatus, or the said signal-receiving apparatus at that station, on any pair of wires, while maintaining it disconnected from any of the other apparatus at the same station, and when the said telephone apparatus is cut in on the said any pair of wires, maintaining it in a balanced local circuit.

17. In an intercommunication telephone system, two groups of local wiring at each station, keys at each station, each group of wiring being connected to a separate pair of contact-springs on the keys by an independent pair of wires, one group including the telephone and signal-sending apparatus, switching contacts located in and forming a part of the apparatus located in this last-named group, the other group being the signal-receiving group of wiring, and including visual signals and an audible signal, other switching contacts forming a part of each visual mechanism and operated thereby, the audible signal being connected in multiple with each visual signal through each pair of said switching contacts, whereby the audible signal may operate simultaneously with any one of the visual signals.

18. In an intercommunication telephone system between three or more stations, an organization of interconnecting lines comprising independent wires for respectively connecting any one of said stations with either one of the other stations, a telephone at each station and normally out of circuit, a balanced local circuit at each sta-

tion and in which said telephone is maintained when connected with any of said interconnecting lines, and separate switches at each station, one for connecting each interconnecting line with the said telephone, and to connect any two telephones at different stations together over the corresponding interconnecting line it being necessary to close two of said switches, one switch at the station calling and one switch at the station called, whereby, when any two or more of said stations are mutually connected together in a circuit for telephoning, no other station can connect in or listen on the last-named circuit.

19. An intercommunication telephone system consisting of the combination of interwiring connecting three or more stations with one another, telephone apparatus at each station, signal-sending apparatus at each station, a group of wiring for said telephone and signal-sending apparatus, located at each station, signal-receiving apparatus and a group of wiring therefor at each station, and devices at the respective stations for electrically connecting the interwiring between any two stations, first to one group of wiring at one station, and then to the other group at the same station, said interwiring comprising independent wires, for respectively connecting the apparatus at each one of the stations, with the apparatus at each one of the remaining stations, said devices consisting of a switch, two of whose terminals are connected to said interwiring, two to one of said groups, and the remaining two to the other group.

20. An intercommunication telephone system consisting of the combination of interwiring connecting three or more stations with one another, telephone apparatus at each station, signal-sending apparatus at each station, a group of wiring for said telephone and signal-sending apparatus, located at each station, signal-receiving apparatus and a group of wiring therefor at each station, and devices at the respective stations for electrically connecting the interwiring between any two stations, first to one group of wiring at one station, and then to the other group at the same station, said interwiring comprising independent wires, for respectively connecting the apparatus at each one of the stations, with the apparatus at each one of the remaining stations, said devices consisting of a switch, two of whose terminals are connected to said interwiring, two to one of said groups, and the remaining two to the other group, and a wedge for controlling the connections of all the terminals.

21. An intercommunication telephone system consisting of the combination of telephone, signal-sending and signal-receiving apparatus, located at each of three or more stations, a system of interconnecting lines

- comprising independent wires, for respectively connecting the apparatus at each one of the stations with the apparatus at each one of the remaining stations, two groups of local wiring at each station, keys at each station, each group of wiring being connected to a separate pair of contact-springs on the keys by an independent pair of wires, one group including the telephone and signal-sending apparatus, switching contacts located in and forming a part of the apparatus located in this last-named group, the other group being the signal-receiving group of wiring, and including visual signals and an audible signal, other switching contacts forming a part of each visual mechanism and operated thereby, the audible signal being connected in multiple with each visual signal through each pair of said switching contacts, whereby the audible signal may operate simultaneously with any one of the visual signals.
22. An intercommunication telephone system consisting of the combination of interwiring connecting three or more stations with one another, telephone apparatus at each station, signal-sending apparatus at each station, a separate group of wiring for said telephone and signal-sending apparatus, located at each station, signal-receiving apparatus and a separate group of wiring therefor at each station, and devices at the respective stations for electrically connecting the interwiring between any two stations, to either one of the said groups of wiring at one station and at the same time maintaining the interwiring between said any two stations disconnected from the other said group of wiring at the same station, said interwiring comprising independent wires for respectively connecting the apparatus at each one of the stations, with the apparatus at each one of the remaining stations.
23. An intercommunication telephone system consisting of the combination of interwiring connecting three or more stations with one another, telephone apparatus at each station, signal-sending apparatus at each station, a separate group of wiring for said telephone and signal-sending apparatus, located at each station, signal-receiving apparatus and a separate group of wiring therefor at each station, and devices at the respective stations for electrically connecting the interwiring between any two stations, first to one group of wiring at one station, and then to the other group at the same station, and for disconnecting either of said groups of wiring from the interwiring between said any two stations when the other said group is connected thereto.
24. An intercommunication telephone system consisting of the combination of interwiring connecting three or more stations with one another, telephone apparatus at each station, signal-sending apparatus at each station, a separate group of wiring for said telephone and signal-sending apparatus, located at each station, signal-receiving apparatus and a separate group of wiring therefor at each station, and devices at the respective stations for electrically connecting the interwiring between any two stations, first to the signal-receiving group of wiring at one station, and then to the telephone and signal-sending group of wiring at the same station, and for disconnecting either of said groups of wiring from the interwiring between said any two stations when the other said group is connected thereto, said interwiring comprising independent wires for respectively connecting the apparatus at each one of the stations, with the apparatus at each one of the remaining stations.

In testimony whereof I have hereunto subscribed my name this 25th day of October, 1902.

RICHARD M. BEARD.
